PAINT MASK STRUCTURE

James Edward Duggan, Birmingham, Mich.

5 Claims. (Cl. 91—65)

This invention relates generally to paint mask structures adapted during painting or plating operations to protect one or more portions of an article from paint or plating material applied to one or more adjacent portions thereof, and constitutes a continuation-in-part of my application filed May 18, 1942, bearing Serial No. 443,518.

More specifically, this invention refers to masks adapted to be applied to gears, pinions and the like to prevent paint or plating material from contacting or passing onto the teeth of the gears, pinions, etc. when other portions of such articles are painted or plated.

One of the essential objects of the invention is to provide a mask capable of thoroughly protecting the teeth mentioned without in any way interfering with the painting or plating operation.

Another object is to provide a mask that may be quickly and easily applied to and removed from the portions to be protected without marring or impairing any part thereof.

Another object is to provide a mask that is simple in construction and economical to manufacture.

Other objects, advantages and novel details of construction of this invention will be made more apparent as this description proceeds, especially when considered in connection with the accompanying drawing, wherein:

Figure 1 is a fragmentary side elevation of a gear and a mask embodying my invention applied thereto, with parts broken away and in section;

Figure 2 is a fragmentary inside edge elevation of the mask illustrated in Figure 1 and showing a transverse section therethrough:

Figure 3 is a side elevation of the mask per se, with parts broken away and in section.

Referring now to the drawing, 10 is the body and 11 are the teeth of a gear A that may be used in any suitable capacity, for example in a governor for an airplane, and B' is a mask embodying my invention for protecting the teeth 11 from paint or plating material applied to the body 10.

As shown, the mask B' is in the form of an annulus and has a solid body portion 12 and a pair of oppositely inclined inwardly extending flanges 20 and 21 respectively. Preferably the mask B' is formed of resilient material such as rubber or rubber composition and is adapted to straddle the teeth 11 of the gear. In this connection it will be noted that the flanges 20 and

21 are relatively thick and constitute extensions of opposite sides of the body portion 12. Preferably such flanges 20 and 21 have sufficient depth to reach opposite sides of the body 12 of the gear when the mask is applied thereto and thus preclude any paint or plating material entering the spaces 30 between the teeth 11 of the gear from either side thereof.

Preferably the resilient one piece mask B' is provided between the side flanges 20 and 21 with radially extending internal teeth 22 for mating with the teeth 11 of the gear A. As shown, the side flanges 20 and 21 incline or converge inwardly from the body portion 12 and are provided at their inner free edges with inwardly projecting lateral flanges 23 and 24 respectively which overlap slightly the internal teeth 22 of the mask. Preferably the teeth 22 of the mask extend between and are terminally connected to the converging side flanges 20 and 21 respectively. Thus, the teeth 22 of the mask are narrower or shorter than the teeth 11 of the gear and are adapted to be stretched and placed under tension in surface to surface engagement with the working surfaces of the teeth 11 of the gear when the mask is applied to the gear.

In use, the mask B' may be applied to the gear A by first lifting either side flange 20 or 21 over the teeth 11 of the gear while the mask is in tilted position relative to the gear so that such teeth 11 may be received in the space between said side flanges 20 and 21 and may register with the spaces 25 between the teeth 22 of the mask. Then the mask B' is stretched from said tilted position over onto the teeth 11 of the gear to the operative masking position illustrated in Figure 1 so that the teeth 11 of the gear will be received in the spaces 25 between the teeth 22 of the mask, and the flanges 20 and 21 of the mask will be in surface to surface relation with opposite sides of the gear. When the mask is in this operative masking position, the teeth 22 of the mask are stretched and under tension in surface to surface engagement with the working surfaces of the teeth 11 of the gear and thereby will effectively cover and protect such surfaces. Hence, the exposed portions of the body 10 of the gear may be safely painted or plated without any of the paint or plating material reaching the teeth 11 of the gear or the spaces 30 between said teeth. In this connection it will be noted that the lateral flanges 23 and 24 are also under tension and tightly engage opposite sides of the gear to accurately define the border or margin of the area that is to be protected.

When it is desired to remove the mask B' from the gear A after the painting or plating operation, the mask may be tilted relative to the body of the gear until one side flange of the mask clears the teeth 11 of the gear.

What I claim as my invention is:

1. A mask for protecting the teeth at the periphery of a gear, pinion and the like from paint and plating material applied to other portions of said article, comprising an annulus of channel cross section adapted to straddle the periphery of said gear and provided between opposite sides of the channel with teeth for surface to surface mating engagement with the teeth of said gear.

2. A mask for protecting the teeth at the periphery of a gear, pinion and the like from paint and plating material applied to other portions of said gear comprising an annulus of channel cross section adapted to be stretched over the periphery of said gear and provided between opposite sides of the channel with teeth for surface to surface engagement with the teeth of said gear.

3. Means for protecting the working surfaces and opposite ends of circumferentially spaced transversely extending teeth of a gear from paint or plating material applied to the body portion of the gear, comprising a resilient relatively elastic one piece solid annular masking element having an interior surface substantially less than the exterior surface of said gear so that said masking element may be fitted by stretching it under tension onto the teeth of said gear, said masking element having projections so spaced and of such depth and thickness that when the masking element is fitted as aforesaid said projections will be squeezed into snug, non-slip surface to surface engagement with the working surfaces of the teeth of said gear to prevent paint or plating material applied to the body of the gear from contacting said working surfaces, said masking element also having portions adapted to overlie and bear firmly against opposite sides of the gear when the projections of said element are squeezed as aforesaid to prevent paint or plating material applied to the body of the gear from contacting opposite ends of the teeth of said gear and to cooperate with the projections of said element to prevent paint or plating material applied to the body of the gear from entering the spaces between the teeth of said gear.

4. Means for protecting the working surfaces

and opposite ends of circumferentially spaced transversely extending teeth of a gear from paint or plating material applied to the body portion of the gear, comprising a resilient relatively

5 elastic one piece solid annular masking element having an interior surface substantially less than the exterior surface of said gear so that said masking element may be fitted by stretching it under tension over the teeth of said gear, said masking element having laterally spaced annular flanges adapted to overlie and bear firmly against opposite sides of the gear when said element is fitted as aforesaid to prevent paint or plating material applied to the body of the gear from contacting opposite ends of the teeth of said gear, said masking element being provided between said annular flanges with circumferentially spaced transversely extending projections for surface to surface mating engagement with the teeth of said gear, said projections being terminally connected to said annular flanges and being of such depth and thickness that when the masking element is fitted as aforesaid said radial projections will be squeezed into snug non-slip

25 surface to surface engagement with the working surfaces of said teeth and will maintain the annular flanges firmly against opposite sides of the gear, whereby the projections and flanges collectively will prevent paint or plating material applied to the body of the gear from entering the spaces between the teeth of said gear.

5. Means for protecting the working surfaces and opposite ends of circumferentially spaced transversely extending teeth of a gear from paint or plating material applied to the body portion of the gear, comprising a resilient relatively elastic solid annular masking element having an interior surface substantially less than the exterior surface of said gear so that said masking element may be fitted by stretching it under tension over the teeth of said gear, said masking element having portions adapted to be squeezed into snug non-slip surface to surface engagement with the working surfaces of the teeth of said gear and having other portions adapted to overlie opposite ends of the teeth of said gear when the element is fitted as aforesaid to prevent paint or plating material applied to the body of the gear from contacting the ends and working surfaces of the teeth of said gear.

JAMES EDWARD DUGGAN.
